UNITED STATES PATENT OFFICE.

LOUIS K. ASCHER, OF INDIANAPOLIS, INDIANA, ASSIGNOR, BY MESNE ASSIGNMENTS, TO THE HUMIDITY CONTROL COMPANY, OF INDIANAPOLIS, INDIANA, A CORPORATION OF INDIANA.

VACUUM RETURN BOILER FEED.

Application filed April 12, 1920. Serial No. 373,177.

It is the object of my invention effectively and economically to produce and maintain the vacuum in a vacuum heating system.

The accompanying drawing illustrates my invention. The single figure of such drawing is a somewhat diagrammatic view showing the essential elements of my invention.

The boiler 10, of any type, supplies steam through a supply pipe 11 to any desired number of radiators 12; and the discharge sides of such radiators are connected through a return pipe 13 to a vacuum tank 14, from which the condensed water is returned to the boiler 10 by a pipe 15 in which is a suitable pump 16 for moving the water through such pipe. The pipe 15 opens into the vacuum tank 14 at a point above the bottom thereof, to avoid taking in any sediment which the water may contain; and in such pipe 15 there is a check valve 17 between the pump 16 and the boiler 10 for preventing backflow from the boiler to the pump. The vacuum tank 14 may be provided with a suitable drain pipe 18; and in the pipe 13 there is preferably a steam-strainer 19 to remove any sediment from the water and steam returning through such pipe to the vacuum tank 14.

I produce and maintain the vacuum in the tank 14 by an injector 20, which has a suction connection to the upper part of the tank 14 by a pipe 21 in which is a check valve 22 preventing back-flow into the vacuum tank. The injector 20 is supplied with water from and returns water to an auxiliary tank 23 provided with an atmosphere vent 24, which auxiliary tank is partly filled with water to an intermediate level indicated by a water gage 25. The water from the water tank 23 is supplied to the injector 20 by a pump 26, the intake of which is connected by a pipe 27 to such water tank, preferably at a point above the bottom of the latter, and the discharge of which leads by a pipe 28 to the water jet 29 of the injector 20. Such water jet discharges the water through the injector 20 into a return pipe 30 leading from the injector to the water tank 23. The water tank 23 also has a suitable drain pipe 31.

The two pumps 16 and 26 are conveniently driven in common by an electric motor 32, to which both pumps are directly connected. The operation of the motor 32 is controlled in response to the vacuum conditions in the vacuum tank 14, by a vacuum-responsive

regulator 33, responsive to the vacuum in the vacuum tank 14 and controlling a switch in the supply wires 34 leading to the motor 32; the present invention is not concerned with the details of the regulator 33.

In operation, the motor 32 drives the pumps 16 and 26 whenever the vacuum in the tank 14, and therefore the vacuum in the system, falls below the desired value. The pump 26 circulates water from the water tank 23 through the pipes 27 and 28, the injector 20, and the pipe 30 back to the water tank 23. The action of the injector 20 draws air (and perhaps some water vapor, but no liquid water,) from the vacuum tank 14 through the pipe 21 and check valve 22, which air (with any water vapor) is carried through the pipe 30 into the water tank 23 along with the water circulating from and to such water tank. This injector action produces and maintains in the vacuum tank 14 a very high vacuum. The pump 16 takes from the vacuum tank 14 any water above the level of the intake end of the pipe 15, and delivers such water to the boiler 10; which boiler supplies the steam to the radiator 12 by way of the supply pipe 11, the water of condensation being taken from the radiator 12 to the vacuum tank 14 by the return pipe 13. The motor 32 and the pumps 16 and 26 driven thereby are started and stopped when the vacuum in the tank 14 respectively falls below and rises above a predetermined value.

I claim as my invention:

1. A vacuum producer, comprising a vacuum tank for connection to a device in which the vacuum is to be produced, an injector having a suction connection to the vacuum tank to produce and maintain a vacuum in the latter, a pump for forcing water through said injector, and a vacuum-responsive device responsive to the vacuum in said vacuum tank for controlling the operation of said pump.

2. A vacuum producer, comprising a vacuum tank for connection to a device in which the vacuum is to be produced, an injector having a suction connection to the vacuum tank to produce and maintain a vacuum in the latter, a water tank, a circulating pipe system from said water tank to the injector and back to the water tank, a pump in said circulating pipe system for circulating water from the water tank therethrough, and

a vacuum-responsive device responsive to the vacuum in the vacuum tank, for controlling the operation of the pump in said circulating pipe system.

5. In an apparatus of the character described, the combination of a tank, means for delivering gases and water of condensation from a heating system to said tank, a pump connected with the tank, and means controlled by the water level in said tank for admitting water from the tank to said pump, whereby such surplus water is delivered under pressure to a boiler or the like.

10. 4. In an apparatus of the character described, the combination of a tank, means for delivering gases and water of condensa-

tion from a heating system to said tank, a surplus water delivery pump adapted to be connected with a boiler or the like, and means for establishing communication between said pump and the interior of the tank at the height of the desired maximum water level therein.

15. 5. In an apparatus of the character described, the combination of a tank, means for delivering gases and water of condensation from a heating system to said tank, a centrifugal pump, and a pipe establishing continuous communication between said pump and the interior of said tank at the desired water level therein.

LOUIS K. ASCHER.
